UNITED STATES PATENT OFFICE

153,011

DESIGN FOR A HOLDER FOR SUCTION
CLEANER ACCESSORIES

Ralph C. Osborn, Bloomington, Ill., assignor to
Eureka Williams Corporation, Detroit, Mich., a
corporation of Michigan

Application June 24, 1946, Serial No. 130,960

Term of patent 14 years

(Cl. D33—8)

To all whom it may concern:

Be it known that Ralph C. Osborn, a citizen of the United States of America and a resident of Bloomington, in the county of McLean and State of Illinois, has invented a certain new, original, and ornamental Design for a Holder for Suction Cleaner Accessories, of which the following is a specification, reference being had to the accompanying drawings, forming a part thereof and wherein:

Fig. 1 is a perspective view of one side of a holder for suction cleaner accessories embodying my new design; and

Fig. 2 is a perspective view of the opposite side.

I claim:

The ornamental design for a holder for suction cleaner accessories, substantially as shown.

RALPH C. OSBORN.
